UNITED STATES PATENT OFFICE.

ISAAK KLEINBERGER, OF NEW HAVEN, CONNECTICUT.

SAFETY-POCKET.

SPECIFICATION forming part of Letters Patent No. 484,435, dated October 18, 1892.

Application filed July 6, 1892. Serial No. 439,136. (No model.)

To all whom it may concern:

Be it known that I, ISAAK KLEINBERGER, of New Haven, New Haven county, Connecticut, have invented an Improved Safety-Pocket, of 5 which the following is a specification.

This invention relates to a safety-pocket for vests and other garments which, though permitting the free introduction of a watch, will prevent an unauthorized withdrawal of 10 the same.

The invention consists in the various features of improvement more fully pointed out in the claim.

In the accompanying drawings, Figure 1 15 represents a vest provided with my improved safety-pocket; Fig. 2, a detail view of the section *a* detached; Fig. 3, a detail view of section *b* detached; Fig. 4, a detail view of section *c* detached. Fig. 5 shows the two sections *b* *c* superposed. Fig. 6 shows the two sections *a* *b* superposed. Fig. 7 shows the 20 three sections *a* *b* *c* superposed.

The letters *a* *c* represent two substantially-square pieces or plies of lining or textile fabric, having an inclined base *a'* *c'* and a cut-away corner *a''* *c''*. The two sections *a* *c* are 25 of the same size and are placed one upon the other with an intervening section or ply. This intervening section *b* is of about half the size 30 of either of the sections *a* *c*, being of approximately-triangular form and having a cut-away end *b'*. The section *a* is the outside piece or piece nearest the vest, then comes the central piece *b*, and then the inside piece *c* or piece nearest the body. 35

In attaching the several parts the central piece *b* is sewed to the inside piece *c* by a diagonal suture *d*, that extends from one corner to about the middle of the diagonal 40 side *b*². A second suture *d'* runs down the lower half of the diagonal side *b*². The upper half of this side, however, remains detached, Fig. 5, to form an opening of a size to correspond with the size of the watch.

45 Against the opposite face of the piece *b* there is laid the outside piece *a*. All the parts are connected together at their sides and base by the suture *e*. Furthermore, the piece *a* is connected to the piece *b* by a top suture *f* and to 50 the piece *c* by a short top suture *g*. Thus the

various plies are connected in the following manner: The plies *b* *c* by a diagonal seam *d* and an inner seam *d'*, the plies *b* *a* by an upper seam *f*, the plies *a* *c* by an upper seam *g*, and the plies *a* *b* *c* by an outer seam *e* at the 55 sides and base. The pocket composed of the parts *a* *b* *c* is attached to the vest A, back of the watch-receiving slit *g'*, as usual. As the parts *a* *b* are connected on top by the suture *f*, the watch introduced at the point *h* will 60 enter between the pieces *b* *c* and be guided down the inclined suture *d*, that connects the same. The watch will thus arrive beyond the inclined edge *b*² of the middle piece *b*, and as the piece *b* stops at such edge the watch will 65 enter between the pieces *a* *c*. The watch will be guided by the beveled edges *a*² *c*² into the corner *m*, and as the parts *b* *c* are connected at the bottom by the suture *d'* it will 70 slip over such suture and overlap the same. (Dotted lines, Fig. 7.) If an unauthorized person attempts to withdraw the watch, he will pull it upward; but the watch will always remain between the parts *a* *b*, and will thus 75 strike against the sutures *f* *g*. Thus its withdrawal is effectively prevented.

If the owner wishes to withdraw the watch, he must slightly press the free or upper part of the edge *b*² sidewise, so that the watch is 80 guided into the mouth formed between the parts *b* *c* above inclined suture *d*. Now the watch may be readily drawn out, as it will pass up along the suture *d* until it arrives at the disconnected upper edge between the parts *b* and *c*. 85

What I claim is—

A pocket composed of two external plies *a* *c* and an inclosed triangular ply *b*, of which the plies *b* *c* are connected by a diagonal seam *d* and an inner seam *d'*, the plies *b* *a* by an 90 upper seam *f*, the plies *a* *c* by an upper seam *g*, and the plies *a* *b* *c* by an outer seam *e* at the sides and base, substantially as specified.

In testimony whereof I have hereunto set my hand this 27th day of June, 1892.

ISAAK KLEINBERGER.
